(57) **CLAIM**

The ornamental design for an electric dry shaver, as shown and described.

DESCRIPTION

FIG. 1 is a perspective view of the first embodiment of an electric dry shaver;

FIG. 2 is a front view thereof;

FIG. 3 is a right side view thereof;

FIG. 4 is a rear view thereof;

FIG. 5 is a left side view thereof;

FIG. 6 is a top plan view thereof;

FIG. 7 is a bottom view thereof;

FIG. 8 is a perspective view of the second embodiment of an electric dry shaver;

FIG. 9 is a front view thereof;

FIG. 10 is a right side view thereof;

FIG. 11 is a rear view thereof;

FIG. 12 is a left side view thereof;

FIG. 13 is a top plan view thereof;

FIG. 14 is a bottom view thereof;

FIG. 15 is a perspective view of the third embodiment of an electric dry shaver;

FIG. 16 is a front view thereof;

FIG. 17 is a right side view thereof;

FIG. 18 is a rear view thereof;

FIG. 19 is a left side view thereof;

FIG. 20 is a top plan view thereof; and,

FIG. 21 is a bottom view thereof.

The broken lines illustrate portions of the electric dry shaver and form no part of the claimed design.

1 Claim, 21 Drawing Sheets
